UNITED STATES PATENT OFFICE

109,729

DESIGN FOR A CHAIR

Dwight Powell, Youngstown, Ohio, assignor to
The General Fireproofing Company, Youngstown, Ohio, a corporation of Ohio

Application April 9, 1938, Serial No. 76,399

Term of patent 14 years

To all whom it may concern:

Be it known that I, Dwight Powell, a citizen of the United States, residing at Youngstown, in the county of Mahoning and State of Ohio, have invented a new, original, and ornamental Design for a Chair, of which the following is a specification, reference being had to the accompanying drawing, forming part thereof.

The figure is a perspective view of a chair showing my new design.

The essential features of my design are shown in full lines.

I claim:

The ornamental design for a chair, as shown and described.

DWIGHT POWELL.
